UNITED STATES PATENT OFFICE.

ERNEST PENBERTHY, OF DETROIT, MICHIGAN, ASSIGNOR TO CHICAGO PNEUMATIC TOOL COMPANY, OF NEW YORK, N. Y., A CORPORATION OF NEW JERSEY.

PERCUSSIVE TOOL.

Application filed May 23, 1925. Serial No. 32,270.

This invention relates to fluid pressure tools of the percussive type. While the invention has features of general utility it is particularly applicable to tools of the portable or hand supported type.

One object of the invention is to provide an efficient and economical tool particularly adapted for use with small portable air compressors for road and contract work. An other object is to provide a percussive machine which will operate well under varied conditions of fluid pressure such as obtain with the small portable operating units used on temporary jobs which provide a limited amount of motive fluid and frequently at relatively low pressures. Other objects will be apparent from the detailed description which follows:

The invention comprises a percussive tool in which the motive fluid is expansively used and its supply largely controlled by the piston on the rearward stroke of the latter and in which the motive fluid is non-expansively used under control of a valve on the forward or work producing stroke of the piston.

In order to illustrate the invention a preferred embodiment thereof is shown in the accompanying drawings in which:

Fig. 1 is a longitudinal sectional view of the essential parts of a drilling machine; and

Fig. 2 is a view similar to Fig. 1 but showing the movable parts in a different position.

The percussive machine disclosed comprises a cylinder 3 providing a piston chamber in which reciprocates a hammer piston 4 arranged to deliver blows to a working tool or drill steel 5 supported in a front head or chuck 6 either directly or through an anvil 7 which may be supported in a guide block 8 interposed between the front head 6 and the cylinder 3. The rear end of the piston chamber is closed by a back head 9 which may contain the motive fluid supply passage 10 which divides into two branches 10^a and 10^b. Branch 10^a terminates adjacent the head 11^a of a spool valve mounted for reciprocatory movement in a valve chamber 12 in timed relation with piston 4. The head 11^b of the valve controls an exhaust passage 13 leading to atmosphere. The valve has intermediate the heads 11^a and 11^b a reduced portion or neck 11^c and from the central portion of the valve chamber 12 there extends to the rear end of the piston chamber 55 a passage 14 which is thus in communication

either with the live air branch 10^a or with exhaust passage 13 dependent upon the position of the valve. From the end face of head 11^b of the valve extends a passage 15 which communicates with the piston chamber in spaced relation to the rearward end thereof so as to be under control of piston 4. A live air passage 15^a of limited size extends from branch 10^b to passage 15.

Branch 10^b leads toward the front of the drill cylinder 3 terminating in a port 10^c approximately midway of the piston chamber, piston 4 being of such length relative to its chamber as never to uncover port 10^c. When the piston 4 is at or near the forward limit 15 of its working stroke an annular groove 4^a on the exterior thereof serves to effect communication between port 10^c and the axially spaced ports 16 and 17. Port 16 forms a part of passage 16^a leading to and controlled 75 by the head 11^a of the valve. Port 17 forms part of a longitudinally disposed passage 17^a terminating at one end in a port 17^b communicating with the forward end of the piston chamber and terminating at the other 80 end against the end face of valve head 11^a. Piston 4 also controls the main exhaust ports 18 and 19 leading direct to atmosphere.

The operation of the tool is as follows: With the parts in the position shown in 85 Fig. 1 piston 4 is beginning its forward stroke with live motive fluid passing from the supply passage 10 through branch 10^a around the neck 11^c of the valve and through passage 14 to the rear end of the piston chamber. The front end of the piston chamber is open to exhaust through port 19. As the piston advances it closes exhaust 19 whereupon the air trapped in the forward end of the piston chamber is forced back into 90 passage 17^a. An instant later the groove 4^a in the piston effects communication between the cross ports 10^c and 16 whereupon passage 16^a is filled with motive fluid from branch 10^b. This priming of passage 16^a may be assisted, if desired, by a constantly open live air port 20 of limited size communicating with branch 10^b. On further movement of the piston 4 the rear end of the piston chamber is opened to exhaust through port 18 100 producing an immediate fall in pressure, which fall is effective on the end of head 11^b of the valve through passage 15. At practically the same instant port 17 comes 105 into communication with groove 4^a where- 110

upon passage 17^a is immediately filled with motive fluid from branch 10^b, which motive fluid is promptly effective through port 17^b in starting piston 4 rearwardly and also in throwing the valve to its rearmost position (Fig. 2). The movement of the valve establishes communication between passages 16^a and 17^a and the motive fluid heretofore trapped in passage 16^a immediately becomes available to assist in the rearward movement of piston 4. At the beginning of the rearward stroke of the piston port 17 is promptly closed but live air still passes to passage 16^a, thence to passage 17^a and thence to the forward end of the piston chamber until the cross ports 16 and 10^c are closed. The piston then continues its rearward movement by expansion of the motive fluid at its forward end until exhaust port 19 is uncovered. As the piston continues its movement by momentum the pressure falls rapidly in the forward end of the piston chamber but there is still sufficient pressure in passages 16^a and 17^a to maintain the valve in its rearward position, particularly since the rear end of the piston chamber is open to exhaust through passage 14, valve chamber 12 and exhaust port 13. The piston then closes the end of passage 15 and the live motive fluid admitted through restricted port 15^a promptly builds up and becomes effective to shift the valve back to its original position shown in Fig. 1 as the piston uncovers port 19 thus venting passages 17^a and 16^a and relieving the pressure on the forward end of the valve. This completes the cycle.

To prevent a delay in the forward shifting of the valve in the event that the momentum of the piston carries it rearwardly sufficient to bring groove 4^a into register with port 15, a restricted live air port 21 is provided in communication with branch 10^b and disposed slightly in advance of passage 15 to prime the groove 4^a and prevent an undesired drop in pressure in passage 15. Port 21 also serves to assist port 15^a in building up pressure in passage 15 when the piston has stopped or is at rest in the rear end of the piston chamber. The piston is preferably hollowed out as indicated at 4^b on its rearward end to lighten its weight and to increase the volume of the rear end of the piston chamber. This is found to increase the speed of the piston and the power of the blow.

From the above it will be apparent that the present invention sets forth a tool of simple and rugged construction, economical in the consumption of motive fluid, and developing the maximum of power from the motive fluid used. Although the preferred form of the invention has been herein shown and described, it is to be understood that the invention is not confined to the specific details thereof, but covers all changes, modifi-

cations and adaptations within the scope of the appended claims.

I claim as my invention:

1. In a fluid pressure percussive tool, a cylinder providing a piston chamber, a piston reciprocable therein, a valve controlling the supply of motive fluid to one end of the piston chamber, means controlled by said piston for directing motive fluid to the other end of the piston chamber, and means controlled by said valve for continuing the supply of motive fluid to the last named end of the piston chamber after said first named means becomes inoperative. 70

2. In a fluid pressure percussive tool, a cylinder providing a piston chamber, a piston reciprocable therein, a valve moving in timed relation with the movements of said piston, means controlled by said valve for supplying motive fluid to one end of the piston chamber, independent motive fluid supply means controlled by said piston for the other end of the piston chamber, and piston and valve controlled means for prolonging the supply of motive fluid to the last named end of the piston chamber after said second named means becomes inoperative. 80

3. In a fluid pressure percussive tool, a cylinder providing a piston chamber, a piston reciprocable therein, a valve controlling the supply of motive fluid to one end of the piston chamber, and means controlled by said piston for directing motive fluid to the other end of the piston chamber, said means comprising longitudinally spaced ports in the cylinder wall leading to the front end of the piston chamber and to the valve respectively and a groove in the piston arranged to connect said ports with the motive fluid supply. 95

4. In a fluid pressure percussive tool, a cylinder providing a piston chamber, a piston reciprocable therein, a valve controlling the supply of motive fluid to one end of the piston chamber, and means controlled by said piston for directing motive fluid to the other end of the piston chamber comprising passages having longitudinally spaced ports in the cylinder wall, a groove in the piston arranged to span said ports and connect the same with the motive fluid supply, said ports and passages being so arranged as to direct motive fluid to the end of the piston chamber when the second port is connected to the motive fluid supply on movement of the piston in one direction but to continue the admission until the first port is closed by the piston on its reverse movement. 100

5. In a fluid pressure percussive tool, a cylinder providing a piston chamber, a piston reciprocable therein, a valve controlling the supply of motive fluid to one end of the piston chamber, and means controlled by said piston for directing motive fluid to the other end of the piston chamber, comprising passages having longitudinally spaced ports in 115

the cylinder wall, a groove in the piston arranged to span said ports and connect the same with the motive fluid supply, said ports and passages being so arranged as to direct 5 motive fluid to the end of piston chamber when the second port is connected to the motive fluid supply on movement of the piston in one direction but to continue the admission until the first port is closed by the piston 10 on its reverse movement, one of said passages being under control of said valve.

6. In a fluid pressure percussive tool, a cylinder providing a piston chamber, a piston reciprocable therein controlling a main 15 exhaust port, a valve controlling the supply of motive fluid to one end of the piston chamber, and means controlled by said piston for directing motive fluid to the other end of the piston chamber comprising longitudinally spaced ports in the cylinder wall 20 and a groove in the piston chamber arranged to connect said ports with the motive fluid supply, said piston being arranged to pass beyond one of said ports to open the same to 25 said main exhaust.

7. In a fluid pressure percussive tool, a cylinder providing a piston chamber, a piston reciprocable therein, having an annular groove, a valve controlling the supply of 30 motive fluid to one end of the piston chamber, a live air passage in said cylinder having a port opening into the piston chamber, and means controlled by said piston for directing motive fluid to the other end of the piston chamber, said means comprising independent 35 passages having ports opening into said piston chamber so positioned as to be connected to said live air port by said groove in the piston, said last named passages being also arranged to be interconnected by said valve, and means for priming one of said last named passages prior to the connection of the other to the motive fluid supply by said piston.

45 8. In a fluid pressure percussive tool, a cylinder providing a piston chamber, a piston reciprocable therein, having an annular groove, a valve controlling the supply of motive fluid to one end of the piston chamber, 50 a live air passage in said cylinder having a port opening into the piston chamber, and means controlled by said piston for directing motive fluid to the other end of the piston chamber, said means comprising independent 55 passages having ports opening into said piston chamber so disposed as to be connected to said live air port by said groove in the piston, said last named passages being also arranged to be interconnected by said valve, 60 and a live air port continuously admitting

motive fluid in limited amount to one of said last named passages.

9. In a fluid pressure operated tool, a cylinder providing a piston chamber, a piston reciprocable therein, a valve controlling the supply of motive fluid to one end of the piston chamber, a passage extending to the opposite end of the piston chamber and to a pressure area of the valve, means controlled by said piston for admitting motive fluid to 65 said passage, and a second passage arranged to form a motive fluid storage chamber of substantial size and to be filled with motive fluid, said second passage being connected to said first passage upon shifting of the valve. 70

10. In a fluid pressure operated tool, a cylinder providing a piston chamber, a piston reciprocable therein, a valve controlling the supply of motive fluid to one end of the piston chamber, a passage extending to the opposite end of the piston chamber and to a pressure area of the valve, means controlled by said piston for admitting motive fluid to 80 said passage, and a second passage also under control of said piston and arranged to be filled with motive fluid in advance of said first named passage to provide a motive fluid storage chamber of substantial size, said second passage being connected to said first passage by said valve on shifting of the same. 90

11. In a fluid pressure operated tool, a cylinder providing a piston chamber, a piston reciprocable therein, a controlling valve therefor moving in timed relation with the piston, said piston having a recess in the exterior thereof, means for shifting said valve by a built up pressure including a vent port under control of said piston, and means preventing said recess from interfering with the control of said valve by said piston. 100

12. In a fluid pressure operated tool, a cylinder providing a piston chamber, a piston reciprocable therein, a controlling valve therefor moving in timed relation with the piston, said piston having a recess in the exterior thereof, means admitting motive fluid continuously in limited amount to a pressure area of said valve, a vent passage extending from said area to the piston chamber to be closed by said piston to cause the continuously admitted motive fluid to build up pressure against said area of the valve, and means for priming said piston recess with motive fluid to insure accurately timed shifting of the valve in the event that said piston recess should register with said vent passage. 110 115
